UNITED STATES PATENT OFFICE.

JOHN J. TOMCHECK, OF TWO RIVERS, WISCONSIN.

FLOOR-JACK.

1,231,461.

Specification of Letters Patent. Patented June 26, 1917.

Application filed November 20, 1916. Serial No. 132,324.

To all whom it may concern:

Be it known that I, JOHN J. TOMCHECK, a citizen of the United States, and resident of Two Rivers, in the county of Manitowoc 5 and State of Wisconsin, have invented certain new and useful Improvements in Floor-Jacks; and I do hereby declare that the following is a full, clear, and exact description thereof.

10 The present invention relates to new and useful improvements in floor jacks, such as used in laying sections of hard wood floors to procure a proper abutting engagement of the boards, and comprising a fulcrum spur 15 and lever means for procuring bearing action of a suitable board engaging shoe.

It is primarily the object of the present invention to simplify and otherwise improve the structure, and to increase the efficiency 20 of floor jacks of this nature, particularly with respect to increasing the readiness of manipulation of such devices.

A further object resides in the provision of a foot controlled fulcrum spur whereby 25 the weight of the operator is utilized to procure a proper anchorage of the jack in its successive operations.

With the above and other objects and advantages in view, invention resides more 30 particularly in the arrangement of bars hereinafter described, and more particularly pointed out in the appended claims.

In the drawings:

Figure 1 is a side elevational view of a 35 floor jack constructed in accordance with the present invention, with portions broken away to more clearly disclose the structure.

Fig. 2 is a top plan view of the jack.

Referring now more particularly to the 40 accompanying drawings, 5 designates the floor board engaging shoe of the jack, which has its face provided with the usual groove 6 for receiving the tenon of a floor board 7, and extending laterally from this shoe is a 45 bar 8 having a longitudinal slot 9 in its rear portion through which is passed a bolt 10 passing also through the lower bifurcated end of the upstanding main lever 11 of the jack. Pivoted on the bolt 10 is a forwardly 50 extending pawl bar 12 having a spur 13 depending from its free end for engagement

in the joist or under flooring 14, and also carrying at said free end a foot rest 12'. Pivoted to the lever 11 and to the shoe carrying bar 8 forwardly of the lever is an 55 arcuate link 15.

Thus upon engaging the spur 13 in the joist or under flooring 14, and swinging the lever 11 forwardly, the shoe 5 will be moved forwardly to properly seat the floor board 60 with which it is engaged. The jack may thus be manipulated in an exceedingly ready manner by a person standing upon the previously laid boards, and by placing his foot on the rest 12', the operator is afforded a 65 bracing means and at the same time the jack is most positively anchored.

While the rear end of the bar 8 has been described as slotted to receive the bolt 10, it is appreciated that any method of slidingly guiding the bar 8 may be utilized; in fact it might not be under all conditions essential to provide a positive guide for the bar. It will be also appreciated that various other changes in the structure herein shown 70 75 may be resorted to without departing from the spirit of invention as interpreted by the accompanying claims.

What is claimed is.

1. A floor jack comprising a board engaging shoe, a lever, a spur carrying bar pivoted to the lower end of the lever for vertical movement, a foot rest on the bar, and a link connected with the shoe and the intermediate portion of the lever. 80 85

2. A floor jack comprising a bar, a shoe at one end of the bar, a lever having its lower end slidingly connected with the other end of the bar, a spur carrying bar pivoted to said lower end of the lever, and a link 90 connected with the intermediate portion of the lever and the first bar.

3. A floor jack comprising a bar provided with a longitudinal slot in one end, a shoe at the other end of the bar, a lever, a spur 95 carrying bar, a bolt passing through the lower end of the lever and through the tooth carrying bar and slidably in the slot of the first bar and a link connected with the intermediate portion of the lever and 100 the first bar.

4. A floor jack comprising a lever, an an-

chor fulcrum therefor pivotally connected therewith, a bar slidably connected with the lever at its pivot, a shoe carried by said bar, and a link connecting the shoe carrying bar and the intermediate portion of the lever.

5 In testimony that I claim the foregoing I have hereunto set my hand at Two Rivers,

in the county of Manitowoc and State of Wisconsin, in the presence of two witnesses.

JOHN J. TOMCHECK.
